UNITED STATES PATENT OFFICE.

ROBERT H. SOUDER AND HOWELL W. SOUDER, OF TAMAQUA, PENNSYLVANIA.

BLOCK-SIGNAL SYSTEM.

1,215,421.

Specification of Letters Patent. Patented Feb. 13, 1917.

Application filed November 18, 1915. Serial No. 62,089.

To all whom it may concern:

Be it known that we, ROBERT H. SOUDER and HOWELL W. SOUDER, citizens of the United States, and residents of Tamaqua, county of Schuylkill, State of Pennsylvania, have invented certain new and useful Improvements in Block-Signal Systems, of which the following is a specification.

This invention relates to an electric block signal system for railroads, the invention being primarily intended for use on electrically operated street railways or inter-urban roads, although its application is not limited to such use.

15 The invention has more particular reference to block signal systems in which the signals are set or cleared by means of an operating current of electricity of momentary duration.

20 The invention has for an object the provision of an improved block signal system adapted to enable cars to follow one another over the block at suitable intervals without waiting for the entire block to clear.

25 A further object relates to the provision of safe guards for the setting of certain signals.

Another object relates specifically to the means for preventing a car, upon leaving a block, from setting the rear signal at clear should there be a following car upon the block.

30 For further comprehension of the invention reference will be had to the following description and accompanying drawings, and to the appended claims in which the various novel features of the invention are more particularly set forth.

In the drawings

35 Figure 1 is a diagrammatic view showing one-half of the block signal system.

Fig. 2 is a similar view of the other half.

40 Fig. 3 is an underside plan view of one of the instruments, embodying certain switches and their controlling magnets and herein designated as machines, constituting part of the system.

45 Fig. 4 is a transverse section on the line 4—4 Fig. 3.

50 Fig. 5 is a similar section on the line 5—5 Fig. 3.

55 Fig. 6 is an underside plan view of another machine.

Fig. 7 is an underside plan view of another machine.

Fig. 8 is a transverse section on the line 8—8 Fig. 7.

Fig. 9 is an enlarged detail transverse section on the line 9—9 Fig. 10.

Fig. 10 is an underside plan view of another machine.

Referring now more particularly to Figs. 1 and 2, reference numeral 1 represents a trolley wire, the complete block extending from the point marked A to the point 65 marked B. The track rails are not shown in the drawing as they are not essential to a proper understanding of the invention.

In the embodiment of the invention herein disclosed three "through block" signals, or 70 signals showing the condition of the block as a whole, are provided at each end of the block, a "clear" signal, indicating that the block is unoccupied, a "permissive" signal, indicating the presence of a car on the block 75 which has entered from the end at which the signal is displayed, and a "danger" signal, indicating that a car is upon the block which has entered from the opposite end. These clear, permissive, and danger signals here 80 comprise respectively a vertical bank of lights 5, a diagonal bank 6, and a horizontal bank 7 located at the end A of the block, and corresponding banks, 5', 6' and 7' located at the end B of the block. 85

In addition to the "through block" signals just referred to there are provided a series of spacer signals, located at desired intervals through the block and dividing it into a number of sections, by means of 90 which a number of cars following one another through the block are kept properly spaced apart.

As here shown these spacer signals comprise clear and danger lights, 10 and 11 respectively, at end A and 10' and 11' respectively at end B while as many of these signals as desired may be spaced throughout the block, the block being divided in the present instance into three sections by the 100 intermediate clear lights 12 and 13, and danger lights 12' and 13'.

Single lights only are preferably provided in the spacer signals to avoid all chance of confusion with the "through" 105 signals.

The signal lights are preferably controlled by magnet-operated switches whose operating current may be received from the trolley wire by contact makers in juxtapo- 110

sition therewith and comprising at end A a cutting in contact maker 15, and a pair of releasing contact makers 16 and 17 connected by a resistance 18, while at end B corresponding contact makers 15', 16' and 17' and resistance 18' are provided. At each of the points where the lights 12 and 13 are located are provided a contact maker 19 adapted to operate where a car is going from A to B, and a second contact maker 20 which operates when a car is going from B to A. As these contact makers are of ordinary construction and the manner in which a momentary flow of current therethrough is caused by the bridging action of the trolley wheel is well known, detail illustration or description thereof is not deemed necessary.

For the sake of convenience the switches which operate together and their controlling magnets are grouped together, each group being designated as a "machine." At each end of the block there are three of these machines, those at end A being designated in the drawing as No. 1, No. 2 and No. 3, the corresponding machines at the opposite end being designated as No. 1', No. 2' and No. 3'. Located adjacent each of the intermediate signals 12, 13 is a machine designated as No. 4.

Machines No. 1 and No. 1' each comprise four switches, designated as 25, 26, 27, 28 and 25', 26', 27' and 28' for the respective machines. Of these switches, 25, 28 and 25', 28' are normally open and 26, 27, 26', 27' are normally closed. In the diagrammatic illustration of the system the switches are all indicated in normal position, or that occupied when the block is clear. Switches 25 and 26 are reversed from normal position by a pair of magnets C and restored to normal position by a pair of magnets D. Switches 27 and 28 are reversed from normal position by a pair of magnets E automatically returning to normal position as will be pointed out later. Similar magnets C' D' and E' are provided on the No. 1' machine.

Machines No. 2 and No. 2' each comprise five switches designated as 30, 31, 32, 33, 34 and 30', 31', 32', 33', 34' for the respective machines. Of these 31, 33 and 31', 33' are normally open and the remaining ones closed. Switches 30, 31 and 32 are operated in unison by a pair of magnets H and switches 33 and 34 by a pair of magnets J, these switches automatically returning to normal position. Machine No. 2' is provided with similar magnets H' and J'.

Machines No. 3 and No. 3' each comprise four switches 35, 36, 37, 38, and 35', 36', 37', and 38' for the respective machines. Of these 35, 36, 35' and 36' are normally open and the others normally closed. Switches 35, 36, 37, 38 are reversed from

normal position by a pair of magnets K and restored to normal position by a pair of magnets L, similar magnets K' and L' being provided for the No. 3' machine.

The No. 4 machines each comprise six switches designated as 40, 41, 42, 43, 44, and 45. Of these 42 and 43 are normally open and the remaining ones normally closed. These switches are all operated to reverse them from normal position by the magnets M, switches 44 and 45 returning automatically to normal position while 40, 41, 42, and 43 are restored to normal position by the magnets N.

The arrangement of the switches and their controlling devices in the different machines is indicated in Figs. 3 to 10 inclusive. The switches are all alike, being of the one-way type with a pair of contacts 50 and 51 and a bridge piece 52, these contacts each having a spring pressed member 50' normally acting to throw the switch to open position. In general these bridge pieces and the armatures 53 of the operating magnets are carried upon arms 54 fixed to rock-shafts 55 suitably mounted in the bearings 56 on an insulating base 57 on which the various magnets are mounted in any suitable manner. The bridge pieces 52 bear upwardly against the contacts 50 and 51 and the parts are so weighted as to be retained in normal position by gravity.

The locking mechanism for switches 25 and 26 of machine No. 1 and the corresponding switches of machine No. 1' is illustrated in detail in Fig. 5 and comprises a detent arm 60 fixed to shaft 55 and adapted to engage in a notch 61 in one end of a bell-crank lever 62 pivoted as at 63 to the base 57 and having the armature 64 of the release magnets D mounted on its opposite end. When the switches are reversed from normal position by the operating magnets the arm 60 rides over the end of the bell-crank lever and engages in the notch 61 causing the switches to remain in reversed position until the release magnet is energized, releasing arm 60 and allowing the switches to return by gravity to normal position.

Machine No. 2 has no locking mechanism. The locking mechanism of the No. 3, 3' and 4 machines is in the main similar to that of the No. 1 machine, comprising an arm 60' fixed to shaft 55 and having a toe 65 adapted to engage in a notch 61' in a bell-crank lever 62' pivoted as at 63' to the base 57 and having the armature 64' of the release magnets mounted thereon. Adjacent the notch 61' in the lever 62' is a projecting lip 66 with which the toe 65 engages when armature 64' is attracted by the magnet thus preventing the releasing of the reversed switches until the magnet is deenergized and its armature falls away.

In the No. 4 machine a supplementary

rock-shaft 55' is provided and has the arm 54 which carries the armature 53 of the operating magnets M fixed thereto, this shaft having a fixed arm 70 projecting under a counterweighted arm 71 fixed to shaft 55. The locking mechanism just described is applied to shaft 55, to which are secured the bridge pieces of switches 40, 41, 42 and 43, while shaft 55' has secured thereto the bridge pieces of switches 44 and 45. It follows then that switches 40, 41, 42 and 43 are locked in reversed position but switches 44 and 45 are open only while the operating magnets are energized. The different machines may be provided with suitable binding posts, (not shown) for the electrical connections.

In the wiring of the system two lines or wires extend from end to end of the block. 20 Through one of these, herein referred to as the operating line, current flows to release the different switches; while through the other line, herein referred to as the signal line, current flows to the spacing signals and 25 to operate certain of the switches.

The operating line extends from A to B as follows: From release contact maker 17, a wire O, in which is a resistance O', leads to switch 38 of machine No. 3. From switch 30 38 a wire O² leads to switch 40 of the nearest No. 4 machine, a wire O³ leading from this switch to the switch 40 of the other No. 4 machine. From switch 40 of this second No. 4 machine, a wire O⁴ leads to switch 38' 35 of the No. 3' machine. From switch 38' a wire O⁵ leads through resistance O⁶ to release contact maker 17'. From wire O, between resistance O' and switch 38, a wire O⁷ leads through magnets D to the ground connection G, a similar wire O⁸ leading from wire O⁵ to the ground connection G' at end B. It will be apparent that under normal conditions the operating line extends unbroken from end A to end B through the 40 different spacer signal machines.

The signal line extends from one bank of danger lights to the other and is traced from end A to end B as follows: From the lights 7 a wire S' leads through magnets H, 50 to switch 34 of machine No. 2. From switch 34 a wire S² leads to switch 26 of machine No. 1. From switch 26 a wire S³ leads to machine No. 3 dividing into two branches, S⁴ and S⁵ respectively, which 55 lead to switches 36 and 37. From switches 36 and 37 branches S⁶ and S⁷ lead to the lights 11 and 10 respectively, re-uniting into a single line S⁸ which leads in a similar manner through branches S⁹ and S¹⁰ to switches 41 and 42 of the first machine No. 4. From switches 41 and 42 branches S¹¹ and S¹² lead to lights 12 and 12'. Again reuniting a wire S¹³ leads similarly to switches 41 and 42 of the other machine No. 60 4 from which switches branches S¹⁴ and S¹⁷

lead to lights 13 and 13'. Again reuniting a wire S¹⁸ leads to switches 36' and 37' of machine No. 3' through the branches S¹⁹ and S²⁰. From switches 36' and 37' branches S²¹ and S²² lead to lights 11' and 10'. Again reuniting a wire S²³ leads to switch 26' of machine No. 1'. From switch 26' a wire S²⁴ leads to switch 34' of machine No. 2' and from switch 34' a wire S²⁵ leads to the danger bank of lights 7'. As each of the banks 7 and 7' is connected to the trolley wire, or other source of electric current, by the wires 80 and 81' respectively, it will be apparent that both ends of the signal line are in feed and that normally no current will flow through it. It will also be apparent that the wiring of the spacing signals 10, 12, 13 and 10' to the normally closed switches 37, 41, 41', and 37' provides a normally closed signal circuit from end to end of the block through the lights 7 and 7'.

From the wire S' connecting magnets H with switch 34, a branch 83 leads to switch 33, and from switch 33 a wire 84 leads to ground. Similar connections 83' and 84' are provided at end B.

Under normal conditions there is a closed circuit through the vertical banks of lights 5 and 5'. This circuit at end A comprises a wire 85 from the trolley connection 80 to the bank 5. From here a wire 86 leads to switch 30 of machine No. 2. From switch 30 a wire 87 leads to switch 27 of machine No. 1, and from switch 27 a wire 88 leads to ground connection G. Similar connections 85', 86', 87' and 88' are provided at end B.

The circuit through the diagonal bank of lights 6, which is normally open, comprises a wire 90 from trolley connection 80 to the bank, a wire 91 from the bank to switch 28 of machine No. 1, and a wire 92 from switch 28 to ground G. It will be apparent that the reversal of switches 27 and 28 will cut out the vertical bank and cut in the diagonal bank. Similar connections 90', 91' and 92' are provided at end B.

From the cutting in contact maker 15 a circuit through magnets C is provided 115 which comprises a wire 95, in which is a resistance 96, leading from the contact maker to magnets C of machine No. 1 and from these magnets a wire 97 leads to switch 32 of machine No. 2, and from this switch a wire 98 leads to ground. Similar connections 95', 96', 97' and 98' are provided at end B. From wire 95 a branch 100 leads to magnets K of machine No. 3 and from these magnets a wire 101 leads to ground 120 providing through these magnets also a circuit from the contact maker to ground. Similar connections 100' and 101' are provided at end B.

From the leg of switch 26, before men- 130

tioned as included in the signal line, to which wire S^3 connects a wire 102 leads to switch 25. From switch 25 a wire 103 leads to magnets E and from the latter a wire 104 leads to ground. Similar connections 102', 103' and 104' are provided at end B.

From trolley connection 80 at end A a wire 105 leads to switch 31 of machine No. 2. From switch 31 a wire 106 leads to magnets J, and from the latter a wire 107 leads to the leg of switch 34 to which wire S^2 , before mentioned, connects. Similar connections 105', 106' and 107' are provided at end B.

15 Referring now particularly to machine No. 3 the release magnets L are connected to the operating line on opposite sides of switch 38 by wires 110 and 111 which connect respectively to the wires O and O^2 .
 20 These magnets L have a normally open connection to ground midway of their winding through a wire 112 leading to switch 35 from which latter a wire 113 leads to ground. Similar connections 110', 111', 112'
 25 and 113' are provided in machine No. 3' at end B.

Referring now particularly to the No. 4 machines, from the contact makers 19 and 20 wires 115 and 116 lead through resistances, 30 117 and 118 respectively, to the operating line on opposite sides of switch 40. These wires are bridged, between the contact makers and the resistances 117 and 118, by a third resistance 119 from the middle of 35 which a wire 120 leads to operating magnets M and from the latter a wire 121 leads to ground.

Release magnets N are connected to the operating line on opposite sides of the switch 40 through the switches 44 and 45, this circuit including a pair of wires 122 and 123 leading from the opposite legs of switch 40 respectively to switches 44 and 45, from which switches wires 124 and 125 respectively, lead to opposite ends of the magnet winding. Magnets N are connected to ground similarly to magnets L, L' by a wire 126 leading to switch 43 from which latter a wire 127 leads to ground.

50 The operation of the system is as follows: It may be stated briefly that when a car enters the block at either end the No. 1, or 1' and 3, or 3' machines at the entrance end and the No. 2, or 2' machine at the far end are operated. When a car enters the block at end A, closing contact maker 15, magnets C are energized, current flowing through wire 95, magnets C, wire 97, switch 32, wire 98 to ground. The energizing of magnets C reverses switches 25 and 26, opening 26 and closing 25, the switches being locked in this position by the device illustrated in Fig. 5. Switch 26 being open the bank 7 is cut out of circuit while the bank 7' is connected to ground G at end A current flowing

through wire S^{25} , switch 34', wire S^{24} , switch 26', wire S^{23} and along the signal line through the No. 3', No. 4 and No. 3 machines, and from the latter machine through wires S^3 , 102, switch 25, wire 103, magnets E, wire 104 to ground G at end A. 70

The energizing of magnets E reverses switches 27 and 28, which as above pointed out are wired respectively to the vertical and diagonal banks of lights, at end A 75 switch 27 opening and cutting out the vertical or clear bank and switch 28 closing and illuminating the diagonal or permissive bank of lights, current flowing from the diagonal bank through wire 91, switch 28, 80 wire 92 to ground G. As the current to energize magnets E must flow through the horizontal or danger bank 7' at the far end of the block it is evident that the setting of the permissive signal 6 is dependent on the 85 setting of the danger signal 7' and is a sign that the car is protected at the far end of the block by a danger signal.

The danger bank of lights 7' is only momentarily in series with the magnets E for 90 the current, as just pointed out, flows through magnets H' of machine No. 2' causing the latter to close switch 31' and open switches 30' and 32'. The opening of switch 30' cuts out the vertical bank of 95 lights 5' at end B, wire 86' leading from the latter being connected to this switch. The opening of switch 32' opens the circuit from the cutting in contact maker 15' through magnets C' to ground, thus preventing a car, inadvertently entering the block from end B from changing the signals in any way. The closing of switch 31' establishes a circuit from the trolley connection 81' through the magnets J' of machine 100 No. 2' to the signal line through wire 105', switch 31', wire 106', magnets J' and wire 107' to the leg of switch 34' to which the portion S^{24} of the signal line connects. The energizing of magnets J' reverses switches 33' and 34', the closing of switch 33' connecting the bank 7' to ground at end B through wires S^{25} , 83' and 84'. As the signal line has previously been put in feed as just noted the magnets J' of machine No. 2' 110 and the magnets E of machine No. 1 remain energized until the current is discontinued by the action of the release contact maker as the car leaves the block. Simultaneously with the energizing of magnets C as the car 115 enters the block current flows from the contact maker 15 along wire 100, through magnets K of machine No. 3 and wire 101 to ground. The energizing of magnets K reverses all four switches of machine No. 3, 120 the opening of switch 37 cutting out the clear light 10 and the closing of switch 36 illuminating the danger light 11 through wires S^7 and S^4 as will be apparent. The opening of switch 38 to which the parts O, 125

130

O^2 of the operating line connect, establishes a break in the operating line, while the closing of the switch 35 grounds the operating line in both directions through wires 5 110 and 111, release magnets L, wires 112 and 113. The purpose of this break and grounding of the operating line will be more fully referred to later. The switches are locked in reversed position by the device 10 illustrated in Fig. 9.

Upon leaving end A the car has set behind it the "through block" permissive signal 6 and the sectional danger signal 11, indicating that there is a car in the first 15 section of the block.

Upon reaching contact maker 19 current flows through wire 115, resistance 117, operating line O^2 , wire 111, one side of magnets L, wire 112, switch 35 and wire 113 to 20 ground. As soon as the car has passed the contact maker 19, the deenergizing of magnet L releases the switches of machine No. 3 and allows them to fall back to normal position. The break in the operating line 25 when switch 38 is opened prevents the current flowing to magnets D of machine No. 1 and releasing the switches of this machine, while as the switches of machine No. 3 are not returned to normal position until the 30 current from the contact maker has ceased there is no possibility of current flowing from the contact maker across switch 38, after the latter has been re-closed to machine No. 1. Simultaneously current flows 35 through resistance 119, wire 120, magnets M and wire 121 to ground. The energizing of magnets M reverses all the switches of machine No. 4, the opening of switch 41 and closing of switch 42 cutting out the clear 40 light 12 and illuminating the danger light 12' while, as in the operation of the No. 3 machine just described, the operating line is grounded on both sides through release magnets N by wires 122 and 123, switches 45 44 and 45, wires 124 and 125, wire 126 which connects to the magnets midway of their winding, switch 43 and wire 127. As will be noted switches 44 and 45 are in the 50 circuit which bridges the operating line across switch 40 through the magnets N. These switches remain open as long as current is flowing through magnets M, but, as will be apparent from the detail description of the No. 4 machines, these switches fall 55 back to normal position as soon as current ceases flowing through magnets M, the other switches, 40, 41, 42, and 43, being locked by the device illustrated in Fig. 9.

When the car reaches the lights 13, 13' 60 the above described operation is repeated. The block may be divided into as many sections as desired, the same operation taking place when a car passes from one section to another, the car setting a danger light behind it on the section it is entering and

establishing a break and grounding of the operating line, while the light is restored to clear and the break in the operating line restored at the entrance to the section it is just leaving.

When the car reaches end B of the block 70 it first closes release contact maker 16', current flowing through resistance O^6 , wire O^5 , switch 38' of machine No. 3', and wire O^4 , energizing magnets N restoring the switches 75 of the last machine No. 4 to normal in the manner above described. As the operating magnets K' of machine No. 3' are wired only to the cutting in contact maker this machine does not operate when a car leaves 80 the block.

When the car reaches contact maker 17' the current travels along the operating line to the release magnets D of machine No. 1 at end A, the circuit being through resistance 18', wire O^5 , switch 38', wire O^4 , switch 40 of the nearest No. 4 machine, wire O^3 , switch 40 of the other No. 4 machine, wire O^2 , switch 38 of the No. 3 machine, wire O and wire O^1 through magnets D to ground 90 G at end A. Switches 25 and 26, being released, fall back to normal position, the closing of switch 26 puts the danger bank 7 into the signal circuit again, while the opening 95 of switch 25 opens the circuit through the magnets J' of machine No. 2', along the signal line, and through magnets E of machine No. 1 to ground. The deenergizing of magnets E causes switches 27 and 28 to fall back to normal position, cutting out the permissive signal 6 and illuminating the clear signal 5. The deenergizing of magnets J' allows switches 33' and 34' to fall back to 100 normal position, thus connecting the horizontal bank of lights 7' to the signal line 105 at end B. Both ends of the signal line being now in feed the lights 7' will cease to glow while the deenergizing of magnets H' will cause switches 30', 31' and 32' to fall back to normal position. The closing of switch 30' closes the circuit from the vertical bank of lights 5' through wire 86', switch 30', wire 87', switch 27', and wire 88' to 110 ground and illuminates these lights. The closing of switch 32' reestablishes the ground circuit from contact maker 15', through wire 95', magnets C', wire 97', switch 32', and wire 98' to ground. The opening of switch 31' disconnects magnets J' from the trolley connection 81'. All the various members 115 of the system have thus been restored to 120 normal position or condition.

Should, however, a second car enter the block before the first car has left the block, the closing of contact maker at B will not 125 operate the release of machine No. 1, as the current will flow to ground through the connection which was established, as above pointed out, at the No. 3 or No. 4 machines, according to the position of the car. The re- 130

lease magnets of the No. 1, No. 3 and No. 4 machines are so wound that the feeble current flowing through resistance 18' and the magnets of No. 3 or No. 4 to ground will not be strong enough to energize these latter magnets but will be sufficiently strong to energize the magnets of No. 1 when a closed circuit is established from end to end of the block. As the arrangement of the system is symmetrical for both ends of the block the operation thereof when a car enters from end B will be readily understood, the contact makers 20 of the No. 4 machines being actuated by a car going from B to A. 10 As many cars can be in the block as the latter is divided into sections. While cars going in the same direction can be leaving and entering the block indefinitely, it will be obvious that any number of cars can follow each other through the block, each car protecting itself at the entrance to each section by a danger signal and establishing an interruption or break in the operating line which prevents all but the last car from 20 turning the system to normal condition when they leave the block, all the breaks being successively made and restored so that when the last car passes from the block the operating line is continuous to permit an operating current to flow over the operating line to the machine that restores the block to normal condition. 25

As many changes could be made in the above construction and many apparently widely different embodiments of our invention designed without departing from the scope thereof we intend that all the matter contained in the above description or shown in the accompanying drawings shall be interpreted as illustrative merely of an operative embodiment of our invention and not in a limiting sense. 35

What we claim is:

1. In a block signal system, a signal at the entrance to a block, operating means adapted to change said signal when a car leaves the block, such means including an operating line extending from end to end of the block, said operating line forming part of a normally open circuit adapted to be closed by a car leaving the block, and means adapted to be operated by a car in the block to prevent an operative operating current flowing in said operating line. 45
- 50 2. In a block signal system, a signal at the entrance to a block, operating means adapted to change said signal when a car leaves the block, such means including an operating line extending from end to end of the block, said operating line forming part of a normally open circuit adapted to be closed by a car leaving the block, and means adapted to be operated by a car in the block to establish a break in said operating line. 55
- 60
- 65

3. In a block signal system a through-block signal at the entrance to a block, operating means therefor adapted to change said signal when a car leaves the block, spacer signals in the block, means adapted to operate said spacer signals, the operation of said last mentioned means preventing change of said through-block signal by the first mentioned means. 70

4. In a block signal system, a through-block signal at the entrance to a block, operating means therefor adapted to change said signal when a car leaves the block, such means including an operating line extending from end to end of the block, spacer signals in the block, means adapted to operate said spacer signals, the operation of such means establishing a break in said operating line. 75

5. In a block signal system, signals at either end of the block, operating means adapted to change the signals at both ends of the block when a car enters or leaves the latter, such means including an operating line extending from end to end of the block, 90 and means adapted to be operated by a car on the block to establish a break in said operating line. 95

6. In a block signal system through-block signals at each end of the block including a permissive signal at one end and a danger signal at the other end, spacer signals in the block, electrically operated means for controlling said signals, and a common operating wire supplying current to the control means of both the through-block and spacer signals. 100

7. In a block signal system, through-block signals at each end of the block including a permissive signal at one end and a danger signal at the other end, operating means therefor including an operating line extending from end to end of the block, spacer signals in the block, electrically operated control means therefor, said control means being connected to the said operating line and adapted to be energized by the current flowing therethrough. 105

8. In an electrically operated block signal system, a through-block signal at the entrance to a block, operating means therefor adapted to change said signal when a car leaves the block, such means including an operating line extending from end to end of the block, spacer signals dividing the block into sections, control means for said spacer signals, the operation of said control means successively establishing an interruption in said operating line and restoring said operating line to its operative condition as a car passes from one section of the block to another. 115

9. In an electrically operated block signal system, a through-block signal at the entrance to a block, operating means there- 120

for adapted to change said signal when a car leaves the block, such means including an operating line extending from end to end of the block, spacer signals dividing the block into sections, control means therefor comprising operating and release devices adapted when a car enters one section to change the adjacent spacer signal and establish an interruption in said operating line and to restore the operating line to its operative condition and change the signal at the entrance to the section it is leaving.

10. In an electrically operated block signal system, a through-block signal at the entrance to a block, operating means therefor adapted to change said signal when a car leaves the block, such means including an operating line extending from end to end of the block, spacer signals dividing the block into sections, control means therefor comprising operating and release devices adapted when a car enters one section to change the adjacent spacer signal and establish an interruption in said operating line and to restore the operating line to its operative condition and change the signal at the entrance to the section it is leaving, the said operating line being wired to the release devices to conduct the energizing current for the latter thereto.

11. In a block signal system a through-block signal at the entrance to a block, spacer signals in the block, means for changing said signals from normal condition, locking mechanisms adapted to retain said signals in changed condition, electrically actuated means for releasing the locking mechanisms, and a common operating wire supplying current to the releasing devices of both the through-block and spacer signals.

12. In a block signal system, a through-block signal at the entrance to a block, spacer signals in the block, means for changing said signals from normal condition, locking mechanisms adapted to retain said signals in changed condition, electrically actuated means for releasing the locking mechanisms, and a common operating wire supplying current to the releasing devices of both the through-block and spacer signals, the operation of the means for changing the spacer signal from normal condition acting to establish an interruption in the said operating line.

13. In a block signal system, a through-block signal at the entrance to a block, spacer signals dividing the block into sections, means adapted to be actuated by the passing of a car for changing said signals from normal condition, locking mechanisms adapted to retain said signals in changed condition, electrically operated means for releasing the locking mechanisms, and a common operating wire supplying current

to the releasing devices of both the through-block and spacer signals, the operation of the means for changing the spacer signals from normal condition acting to establish an interruption in the operating line and ground the latter through the release device between the section the car is leaving and the section the car is entering.

14. In a block signal system, a plurality of signals at either end of the block, electrical connections including switches through which said signals are energized, electrically energized control devices for said switches, a signal line connected to a source of current, a normally open connection from such signal line through said control devices to ground, and means adapted to be actuated by a car entering the block for closing said normally open connection, locking means retaining said connection closed, and releasing means adapted to be actuated by a car leaving the block for permitting such connection to open and the said switches to return to normal position.

15. In a block signal system, a plurality of signals including a danger signal at either end of the block, electrical connections including switches through which said signals are energized, electrically energized control devices for said switches, a signal line, a normally open circuit whereby current is conveyed from said signal line through said control devices to ground to energize said control devices, means adapted to be actuated by a car entering one end of the block for closing said normally open connection, the said signal line being connected to the danger signal at the far end of the block to cause the current actuating said control devices to flow thereto through the said danger signal.

16. A block signal system having through-block signals consisting of a clear signal, a danger signal and a permissive signal at either end of the block, spacer signals dividing the block into sections, and means for changing said through-block signals as a car enters or leaves the block and for changing said spacer signals as a car passes from one section of the block to another.

17. In an electrically-operated block signal system, a signal operating device comprising a plurality of switches, electrically energized devices for reversing said switches from normal position, locking means for retaining said switches in reversed position, and electrically energized devices for releasing said locking means, said locking means being adapted to release only after said devices have been energized and become de-energized again.

18. In an electrically-operated block signal system, a signal operating device comprising a plurality of switches, a rock shaft having the bridge pieces of said switches

3
mounted thereon, and electrically energized magnets whose armatures are also mounted on said rock shaft, a locking device adapted to retain said shaft in the position 5 to which it has been rocked by the said magnets, and an electrically energized magnet adapted to release said locking device, and means preventing movement of said shaft while current is flowing through said last 10 mentioned magnet.

19. In an electrically operated block signal system, a signal operating device comprising a plurality of switches, an operating device for operating all of said switches, and 15 a locking device adapted to lock less than all of said switches.

20. In a block signal system, a through-block signal at the entrance to a block, spacer signals dividing the block into sections, 20 means adapted to be actuated by the passing of a car for changing said signals from normal condition, locking mechanisms adapted to retain said signals in changed condition, 25 electrically operated means for releasing the locking mechanisms, the release devices of the through-block and spacer signals being

operative by currents of varying strength, a common operating wire supplying current to the releasing devices of both the through-block and spacer signals, and a resistance in 30 said operating line adapted to vary the strength of the current flowing through the said release means.

21. In a block signal system, a clear signal, a permissive signal, and a danger signal 35 at each end of the block, the clear signal being normally set and the permissive and danger signals normally extinguished, control means for said danger signals adapted to be actuated when a car enters the block, 40 control means for said clear and permissive signals, the operation of said first mentioned control means closing an electric circuit through the danger signal at one end of the block and also through the last mentioned 45 control means whereby the latter are operated to reverse the clear and permissive signals at the other end of the block.

Signed at Tamaqua, Pennsylvania, this 10th day of November, 1915.
